UNITED STATES PATENT OFFICE.

WILLIAM R. RAMEY, OF WAVERLY, KANSAS.

WATCHCASE-PENDANT.

SPECIFICATION forming part of Letters Patent No. 609,462, dated August 23, 1898.

Application filed November 18, 1897. Serial No. 659,031. (No model.)

To all whom it may concern:

Be it known that I, WILLIAM R. RAMEY, a citizen of the United States, residing at Waverly, in the county of Coffey and State of 5 Kansas, have invented a new and useful Pendant-Bow Lock, of which the following is a specification.

Watches when carried in the pocket cause annoyance to the wearer by the swivel or 10 snap of the chain or guard engaged with the bow getting caught beneath the pendant-crown due to the bow folding against a side of the watch.

Another objection is found in the great 15 wear upon the sides of the watch where the bow strikes and upon the journals or pivot ends of the bow and their bearings in the pendant by the frequent turning and swinging of the bow when free.

20 This invention aims to render the watch-case dust and moisture proof and prevent the bow wearing in its bearings on pendant and turning down on sides of the case and provides a simple and effective means for 25 securing the bow in a given position and preventing the swivel or snap of the guard or chain getting beneath the pendant-crown and yet admit of the bow being released and turned aside when desired for any required 30 purpose.

For a full understanding of the merits and advantages of the invention reference is to be had to the accompanying drawings and the following description.

35 The improvement is susceptible of various changes in the form, proportion, and the minor details of construction without departing from the principle or sacrificing any of the advantages thereof, and to a full disclosure of 40 the invention an adaptation thereof is shown in the accompanying drawings, in which—

Figure 1 is a front view of a pendant and bow, showing the application of the invention. Fig. 2 is a view similar to Fig. 1, partly 45 in section and showing the bow released. Fig. 3 is a detail perspective view of the attachment.

Corresponding and like parts are referred to in the following description and indicated 50 in the several views of the drawings by the same reference characters.

The pendant 1, bow 2, and crown 3 are

of ordinary construction, such as applied to watches of the open-faced type.

The attachment consists of a bar 4 and a 55 flat spring 5, secured at one end thereto, the bar having its end portions bent, as shown at 6, and grooved to receive the inner side of the bow 2. By having the bent ends 60 grooved in their outsides an extended bearing is had for the bow, thereby enabling a firm joint being provided, which will withstand the strain to which the cross-bar will be subjected when in service. The cross-bar is soldered or brazed at its ends to the 65 bow at about diametrically opposite points and strengthens the bow and prevents its pivotal ends from spreading after being sprung into engagement with the bearings formed at the sides of the pendant. The cross-bar is located about centrally of the bow and touches the top side of the crown when the bow is in the plane of the watch to which the lock is applied, and has a notch 7 midway of its ends to admit of a finger-nail reaching the under 70 side of the spring 5 when it is required to press the latter outward to release the bow, as will appear more fully hereinafter.

The spring 5 is placed upon the top side of the cross-bar 4 and is secured at one end 80 thereto and is provided at an intermediate point with a stud 8, projecting through an opening in the bar 4 and beyond the inner side of the said bar a short distance, so as to enter a depression 9 in the top side of the 85 crown 3 and centrally thereof, whereby the bow is locked in the required position. The free end of the spring 5 is supplied with a headed stud or pin 10, which operates in an opening in the bar 4, the head of the part 10 90 engaging with the under side of the bar 4 and limiting the outward movement of the spring at its free end, whereby the said spring is prevented from being moved outward too far at its free end and destroying its elasticity or 95 rupturing the same at or near its connection with the bar 4.

When the bow is locked, the crown 3 is prevented from outward displacement and is held close against the stem, thereby excluding dust, and the swivel or snap of the watch chain or guard being confined in the space formed between the outer half of the bow and the bar 4 cannot get beneath and engage

with the crown 3, and, moreover, the bow is held against swinging or turning, thereby saving wear upon the pivotal ends of the bow and their bearings and preventing a marring 5 of the sides of the case by the outer end of the bow striking the same. When it is required to release the bow for any purpose, the finger-nail is inserted into the notch 7 beneath the spring 5 and the latter pressed outward to withdraw the stud 8 from engagement with the crown, when the bow can be turned to one side or the other.

When the invention is applied to a lever-set watch, the latter can be set and wound 15 without releasing the bow and turning it aside; but when applied to a pendant-set watch the bow must be released and turned aside to allow the winding-stem to be drawn out to set the watch. The lock secures the 20 bow and holds the crown close to the pendant, so as to exclude dust and moisture.

Having thus described the invention, what is claimed as new is—

1. The combination with a pendant and its 25 bow, of a cross-bar secured at its ends to the sides of the bow, and a flat spring applied to the top side of the cross-bar and having a stud passing loosely through an opening formed therein and adapted to interlock with the 30 pendant-crown, substantially as set forth.

2. The combination with a pendant and its bow, of a cross-bar secured at its ends to the sides of the bow at diametrically opposite points, a flat spring applied to the top side of the cross-bar and having a stud passing loosely through an opening therein to interlock with the pendant-crown, and a headed pin or stud provided at the free end of the spring and passing loosely through an opening in the aforesaid cross-bar, substantially 35 as and for the purpose set forth.

3. The combination with a pendant and its bow, of a cross-bar having its ends bent and grooved to receive the side portions of the bow to which they are secured, said bar having a notch midway of its ends, a flat spring applied to the top side of the cross-bar and provided with a stud passing loosely through an opening in the bar to enter a depression in the pendant-crown, and a headed pin or 40 stud applied to the free end of the spring, substantially in the manner and for the purpose specified.

In testimony that I claim the foregoing as my own I have hereto affixed my signature in 45 the presence of two witnesses.

WILLIAM R. RAMEY.
